CLAIM

We claim the ornamental design for a backup gunsight, as shown and described.

DESCRIPTION

FIG. 1 is a front, right, top perspective view of the backup gunsight.

FIG. 2 is a front, left, top perspective view of the backup gunsight of FIG. 1.

FIG. 3 is a rear, right, top perspective view of the backup gunsight of FIG. 1; and,

FIG. 4 is a rear, left, top perspective view of the backup gunsight of FIG. 1.

The bottom appearance of the backup gunsight is not shown in the drawing and forms no part of the claimed design.
